CALIFORNIA.

SLIDING SPRING CLOSURE FOR CONTAINERS.

Application filed March 10, 1925. Serial No. 14,439.

To all whom it may concern:

Be it known that we, FRED V. BELLUOMINI, EUGENE T. BORO, and WILLIAM D. TAM, citizens of the United States, residing at Jackson, in the county of Amador and State of California, have invented certain new and useful Improvements in Sliding Spring Closures for Containers, of which the following is a specification, reference being had to the accompanying drawings.

This invention relates to closures, and particularly to caps for tubes and other containers such as the flexible tubes used for toothpaste, shaving cream, and the like, though the invention is not limited in use to these articles.

Many of the toothpastes, shaving creams, and the like are contained in flexible tubes which are closed by screw caps. This cap is very likely to be lost. The tube is usually used over a lavatory bowl and the cap oftentimes slips down through the drainage opening of the bowl into the outlet pipe and is liable to become caught therein and form an obstruction in the pipe. Furthermore, the cap is relatively small, it slips out of the fingers, is liable to fall upon the floor and be difficult to find, and if the cap is not used the cream becomes hard. While caps have been provided which are connected to the tube so that they cannot readily fall off, it is still necessary to unscrew the cap and screw it back.

The general object of our invention is to provide a container cap which does not screw into place but slides into place, which is resiliently held in its container-closing position, and which is so linked to the neck of the container that it is impossible for the cap to be lost.

A further object is to provide a cap of this character which is connected to the container by a very simple connection, which connection is such as to allow the cap to be slid laterally either to dispose the cap over the mouth of the container or to slide it to one side of the mouth.

A still further object in this connection is to provide means whereby this cap shall be resiliently urged toward the rim of the mouth of the container when the cap has been slid to its closed position.

Another object is to provide a device of this character which is so constructed that the container may be opened and closed, that is, the cap slid to its open or closed position with the thumb and forefinger of one hand, thus making it particularly convenient.

Other objects will appear in the course of the following description.

Our invention is illustrated in the accompanying drawing, wherein:—

Figure 1 is a side elevation of a tubular container showing our improved cap in its closed position;

Figure 2 is a front elevation with the arms 18 in section;

Figure 3 is a top plan view of the container and cap;

Figure 4 is a fragmentary elevation, the neck of the container being partly broken away and the bar 19 being in section;

Figure 5 is a top plan view showing the cap shifted out of its closed position;

Figure 6 is a fragmentary side elevation like Figure 4 showing the cap shifted to its open position.

Referring to this drawing, it will be seen that 10 designates the usual flexible tube within which shaving creams, facial creams, toothpaste, etc., are today sold and carried. This flexible container or tube is contracted at one end, as at 11, and formed with an upstanding rim 12. The opposite end of the tube is, of course, closed by folding the metal of the tube over upon itself, as at 13. So far we have described the ordinary flexible tube such as used for artists' paints and for creams.

The upper end of the neck 12 is formed with a depressed seat 14 which is adapted to be closed by a circular cap 15, the under face of which is convex so as to fit the seat 14. At the base of the neck there is an upstanding portion 16 which is formed with longitudinally extending grooves 17, and operating within these grooves are the lateral bars 18 of a rectangular clip. These bars are made of wire and joined at one end by a cross bar 19, and the opposite ends of the wires forming the bars 18 are extended toward each other and then bent to form a spring 20, one end of the spring

being extended, as at 21, over the cap and soldered or otherwise engaged therewith.

The lateral bars 18 of the link, as before stated, slide in the guides or slots 17, and 5 when the cross piece 19 is pushed the cap 15 will be forced off the top of the neck 12 and carried laterally so as to entirely disclose the mouth. The rim of the neck 12 is formed on that side which faces the 10 spring 20 with a flange 22 having a downwardly and outwardly inclined face so that when the clip 18 is drawn in a direction to carry the cap back upon the mouth of the container, this inclined face of the flange 15 22 will strike the forward edge of the cap and lift the cap so that the cap will slide over the top edge of the rim and then the spring 20 will cause the cap to close down against the seat 14, thus tightly closing the 20 mouth of the container.

It will be seen that this device provides a closure which is tight and secure and yet which may be readily opened by simply holding the container in the hand and pressing 25 the thumb, for instance, on the cross bar 19 to force the cap off, and that the cap may be as readily pulled back into place again. Inasmuch as there is no screw-threaded engagement between the cap and the mouth 30 of the container, the cap may be placed or displaced very quickly and with a minimum of effort. The device is very simple, may be cheaply made, and is readily applied. The spring keeps the metal cap tightly in 35 place when the tube is closed, making the tube air-tight.

While we have described this device as being particularly designed for use with flexible tubes such as are used for tooth- 40 pastes, shaving creams, facial creams, and artists' colors, we do not wish to be limited thereto as it is obvious that it might be used for a large variety of different containers, and the invention is not to be lim- 45 ited to the specific form of the device as illus- trated, as this may be changed in many ways without departing from the spirit of the invention as defined in the appended claims, nor is it to be limited to the par- 50 ticular combination of the cap with a flexi- ble container as illustrated, as the cap may be disposed in other combinations without departing from the spirit of the invention.

We claim:—

55 1. The combination with a container hav- ing a neck and a mouth, of a cap fitting upon the mouth, means slidingly supporting the cap upon the neck of the container for movement in a plane at right angles to 60 the axis of the neck whereby the cap may be moved toward or from the mouth, and means resiliently urging the cap in a direction parallel to the axis of the container and against the mouth.

65 2. The combination with a container hav-

ing a neck and mouth, of a member slid- 70 ingly embracing the neck and movable in a plane at right angles to the axis of the neck, and a cap carried upon said sliding mem- ber and adapted to fit over the mouth.

3. The combination with a container hav- 75 ing a neck and mouth, of a member slid- ingly embracing the neck for movement in a plane at right angles to the axis of the neck, a cap, and a spring operatively connecting the cap to the sliding member and urging the cap parallel to the axis of the neck.

4. The combination with a container hav- 80 ing a neck, of a slide slidingly embracing the neck and having sliding movement in a plane at right angles to the axis of the neck, said slide carrying a coiled spring at one end, the coiled spring having an arm, and a cap supported by said arm and adapted to close the neck in one position of the sliding member and disclose the neck in another position of the sliding member.

5. The combination with a container hav- 85 ing a neck, of a slide mounted upon the neck for sliding movement in a plane at right angles to the neck, a spring carried by said slide, and a cap carried by the spring and urged by the spring in a line parallel to the axis of the neck and adapted in one position of the slide to close the neck and in an- 90 other position to disclose the neck.

6. The combination with a container hav- 95 ing a neck, the neck being formed at one point with a bevel-faced flange and the neck be- ing formed with a cap seat, of a member 100 slidingly engaging the neck for movement diametrically across the neck, a spring car- 105 ried by the member, and a cap carried by the spring and urged downwardly thereby, the beveled flange on the neck acting to lift the cap and permit it to slide over onto the seat.

7. The combination with a container hav- 110 ing a neck, of laterally disposed guides car- ried by the neck, a sliding member includ- 115 ing two laterally disposed, parallel bars en- gaging in said guides, the bars being con- nected at one end, the opposite end of said bars carrying a spring, a cap supported by said spring and adapted to fit over the neck, the cap being urged against the neck by the spring, and means for guiding the cap into position on the neck.

8. A container having a neck, the neck being formed to provide two laterally dis- 120 posed, parallel, grooved guides, a slide mounted on the neck and including two parallel bars sliding in said grooves, the bars being connected by a cross bar at one end, the opposite ends of the bars being ex- 125 tended toward each other and formed to provide a coiled spring having an upwardly extending arm, and a cap carried by said arm, the neck being formed with a seat upon which said cap rests and having a 130

flange extending toward the coiled spring, the upper face of the flange being downwardly and outwardly beveled. neck including means resiliently urging the 10 cap in a direction parallel to the axis of the neck and toward the mouth of the neck.

9. The combination with a container having an outlet neck, of a cap closing the neck, and means slidably supporting the cap upon the neck for movement in a plane at right angles to the axis of the neck and preventing detachment of the cap from the

In testimony whereof we hereunto affix our signatures.
